UNITED STATES PATENT OFFICE.

JOHN GRAVES MCKEAN, OF MOUNT VERNON, AND ROBERT FREDERICK JONES, OF GLASGOW, SCOTLAND.

LIQUID-FUEL FURNACE.

Application filed September 30, 1921. Serial No. 504,311.

To all whom it may concern:

Be it known that we, JOHN GRAVES MCKEAN and ROBERT FREDERICK JONES, engineers, subjects of the King of Great Britain and Ireland and the Isle of Man, residing, respectively, at Westerhill, Mount Vernon, Lanarkshire, Scotland, and 11 Leven Street, Pollokshields, Glasgow, Scotland, have invented new and useful Improvements in Liquid-Fuel Furnaces, of which the following is a specification.

This invention has reference to improvements in and relating to liquid fuel furnaces and has for its object the pre-heating of the air supplied for combustion together with means for regulating the supply of air to the furnace in order to obtain complete combustion.

In order that our said invention and the manner of carrying the same into effect or practice may be properly understood we have hereunto appended one sheet of explanatory drawings in which,—

Figure 1 is a front elevation of a liquid fuel furnace front as constructed according to this invention.

Figure 2 is a sectional elevation taken on the line 2—2 of Figure 1.

Figure 3 is a sectional elevation taken on the line 3—3 of Figure 2 but with the furnace front plate removed.

Figure 4 is an elevation of the primary air trunk shown broken away, and illustrates a slightly modified shape for the vanes which are adapted to impart a swirling motion to the secondary air for complete combustion. In this view two vanes only are shown one at right angles to the other so as to show their shape clearly.

Referring to these drawings:—

In carrying the improvements of this invention into effect or practice a primary air trunk *a* of less diameter than the opening *b* into the furnace is bell-mouthed at its forward end *c* to a diameter *d* greater than the opening *b* into the furnace and is provided at its outer periphery with a sleeve extension *e* closed by an end plate *f* having a valve *g* for the admission of primary air. The liquid fuel atomizer *h* penetrates the end plate *f* and lies concentrically within the primary air trunk *a*. The air trunk *a* is arranged in such a manner that a circumferential space *j* is left between the bell-mouthed termination *c* and the furnace front

plate *i* for the admission of secondary air. A series of vanes *k* adapted to direct the incoming secondary air tangentially to the longitudinal axis of the liquid fuel atomizer *h* is provided round the said circumferential space *j*. Alternatively, and as illustrated by Figure 4, radial vanes *k*¹ shaped at *k*² to the contour of the bell-mouthed portion *c* of the air trunk *a* and deflected at their outlet edges *k*³ may be employed. A cone shaped valve *l* longitudinally movable on the sleeve extension *e* of the air trunk *a*, by means of the handles *m* (Figure 1), regulates the supply of secondary air. A conical screen plate *n* is carried from the end plate *f* of the air trunk *a* in such a manner that a circumferential space *o* is left between the furnace front plate *i* and the screen plate *n*. The furnace front plate *i* which is of conical formation is dished inwardly towards the furnace and the screen plate *n* is dished outwardly so that the space or chamber *o* surrounding the air trunk *a* increases in size longitudinally to the furnace as its diameter gets smaller. This construction besides stiffening the furnace front plate which forms the inner wall of the chamber or space *o* enables the circumferential area of the chamber *o* to be approximately constant for all distances from the center so that the passage of secondary air admitted circumferentially round the chamber *o* is not impeded by being restricted as it nears the vanes *k* and as its temperature rises.

The furnace front plate *i* may carry a screen plate *p* which extends outwardly from the periphery of the cone-shaped valve *l*. A cone-shaped baffle plate *q* arranged round the atomizer *h* is adapted to deflect the air entering through the valve *g*.

The method of working will be as follows:—

Primary air is admitted by the atomizer *h* by means of the valve *g*. The secondary air is heated while passing between the screen plates *n* and *p* and the furnace front plate *i*. The secondary air is regulated by the cone-shaped valve *l* and passing through the tangentially inclined vanes *k* is given a swirling motion and mixes with the atomized liquid fuel on its way to the furnace.

We claim.

1. A liquid fuel furnace front comprising a cylindrical wall arranged horizontally in

front of and centrally in relation to the opening to the furnace in the front plate and of a diameter larger than the diameter of the said opening, an inwardly projecting 5 radial flange at the inner termination of said cylindrical wall, and a plurality of vanes so arranged in the space between said inwardly projecting radial flange and the furnace front plate as to impart to the air 10 moving radially inwardly a movement in a circular or rotary direction; substantially as herein set forth.

2. A liquid fuel furnace front comprising a cylindrical wall arranged horizontally in 15 front of and centrally in relation to the opening to the furnace in the front plate and of a diameter larger than the diameter of the said opening, an inwardly projecting radial flange at the inner termination of 20 said cylindrical wall; a plurality of vanes so arranged in the space between said inwardly projecting radial flange and the furnace front plate as to impart to the air moving radially inwardly a movement in a circular 25 or rotary direction, an air deflecting cylindrical wall of bell-mouth or curved shape so arranged in relation to said vanes that the air moving circularly and radially inwardly has imparted to it a motion in a 30 horizontal direction through the opening to the furnace; substantially as herein set forth.

3. A liquid fuel furnace front comprising a furnace-front plate of dished or conical 35 form constituting the inner wall of a circumferential air space or chamber, a conical screen plate constituting the outer wall of said air space, said walls being oppositely dished, means for forming an air trunk 40 centrally positioned within said air space, and means included in said circumferential air space for successively imparting to the

air passing therethrough circular and spiral motions.

4. In a liquid fuel furnace front, the combination with a front plate having a furnace opening therein, of a cylinder member of greater diameter than said furnace opening positioned in axial alignment therewith and spaced therefrom, the inner end of said cylinder member being provided with a flange terminating in an inwardly curved portion, the edge of which is of reduced diameter with respect to said furnace opening, a closure plate including air-control means secured to the outer end of said cylinder, a sleeve valve for regulating the passage of air through the space between said cylinder flange and said front plate, and means included in said space for directing the air 50 passing therethrough upon said inwardly curved portion in a whirling motion.

5. In a liquid fuel furnace front, the combination with a front plate having a furnace opening therein, of a cylinder member of greater diameter than said furnace opening positioned in axial alignment therewith and spaced therefrom, the inner end of said cylinder member being provided with a flange terminating in an inwardly curved 55 portion, the edge of which is of reduced diameter with respect to said furnace opening, a closure plate provided with air-control means and an atomizer secured to the outer end of said cylinder, a sleeve valve for regulating the passage of air through the space between said cylinder flange and said front plate, screen plates positioned immediately adjacent to said sleeve valve, and vanes positioned in said space for directing the 60 air passing therethrough upon said inwardly curved portion in a whirling motion.

JOHN GRAVES McKEAN.
ROBERT FREDERICK JONES.
